(57) **CLAIM**

The ornamental design for a digital camera, as shown and described.

DESCRIPTION

FIG. 1 is a front, top and right side perspective view of a digital camera showing my new design;

FIG. 2 is a front, top and left side perspective view thereof;

FIG. 3 is a front elevational view thereof;

FIG. 4 is a rear elevational view thereof;

FIG. 5 is a top plan view thereof;

FIG. 6 is a right side elevational view thereof; and,

FIG. 7 is a left side elevational view thereof.

The broken lines depict portions of the digital camera in which the design is embodied that form no part of the claimed design. Additionally, the dash-dot lines denote the boundary of the claim and form no part of the claimed design. The bottom plan views form no part of the claimed design and have been omitted from the drawings.
